UNITED STATES PATENT OFFICE.

LAWRENCE M. PERSONS, OF CHICAGO, ILLINOIS, ASSIGNOR TO COOK ELECTRIC COMPANY, OF CHICAGO, ILLINOIS, A CORPORATION OF ILLINOIS.

STARTING SWITCH FOR MOTORS.

Application filed May 11, 1923. Serial No. 638,207.

To all whom it may concern:

Be it known that I, LAWRENCE M. PERSONS, a citizen of the United States, residing at Chicago, in the county of Cook and 5 State of Illinois, have invented certain new and useful Improvements in Starting Switches for Motors, of which the following is a specification.

In motors, especially of the alternating 10 current type, it is usual to provide a starting circuit which is broken after the motor has attained its normal speed. The present invention relates to a starting switch of this type which shall be economical to manufacture, efficient in operation, and which shall 15 be of long duration.

The invention is exemplified in the combination and arrangement of parts shown in the accompanying drawing and described in 20 the following specification, and it is more particularly pointed out in the appended claims.

In the drawing—

Fig. 1 is a sectional view of a motor showing parts of the starting switch in elevation;

Fig. 2 is a view similar to Fig. 1, having the starting switch parts in section; and

Fig. 3 is a section on line 3—3 of Fig. 2. 30 In the drawing, the numeral 10 designates a motor shaft journaled in bearings 11 on a casing 12. Secured to the shaft 10 is an armature 13 having a cover plate 14 at the end thereof. Field poles 15 are supported 35 by the casing 12 about the armature 13 in the usual manner. A collar 16 is interposed between the end of the armature 13 and the frame 12 to hold the parts in proper spaced relation. Slidably mounted on the collar 40 16 is a sleeve 17 having arms 18 extending radially therefrom at opposite sides thereof.

A pair of arcuate members 19 are provided with hooks 20 which engage openings 21 in the end plate for the armature 13. 45 These arcuate members 19 are provided with coil springs 22, one at each side of the sleeve 17, which tend to draw the members 19 inwardly. The members 19 are perforated at 23 to receive the arms 18 so that the inward movement of the members 19 slides the sleeve 17 to the right, as viewed in Figs. 1 and 2.

The sleeve 17 is provided with a ring 24 secured to the end thereof in position to 50 engage a conductor ring 25. The ring 24

is made of hard fiber or other suitable insulating material. The ring 25 is supported by a series of hooks 26 disposed in circular arrangement about the ring 25 and mounted on an insulation plate 29 secured to the 60 casing 12. The ring 25 is free to rotate in the confines of the supporting hooks 26 and is resiliently pressed to the left, as viewed in Fig. 2, by springs 27 attached to the insulation block 29.

A pair of contact members 28 are mounted on the insulating block 29 on the casing 12 and are in position to engage the contact ring 25 when the ring is pushed to the right by the insulator ring 24, as shown in Fig. 1. 70 The contacts 28 have conductors 30 attached thereto so that when the contacts are connected by the ring 25 the circuit is completed through the starting coils of the motor.

When the armature is at rest the parts are held in the position shown in Fig. 1 by the springs 22 so that the starting circuit is closed. When the armature attains full speed the arcuate members 19 are swung 80 outwardly by centrifugal force to the position shown in Fig. 2, thus retracting the sleeve 17 and withdrawing the ring 24 from contact with the conductor ring 25. This permits the springs 27 to force the conductor 85 ring 25 away from the contacts 28 and break the starting circuit after the motor has attained full speed.

At the time the motor starts to rotate the frictional contact of the ring 25 upon the 90 springs 27 and contact members 28 will hold the ring 25 from rotation and the ring 24 will slide upon the ring 25. When the current is shut off and the motor begins to decrease in speed the ring 24 will engage the 95 ring 25 and since at the time of engagement the ring 25 is free from contact with the terminals 28, it will begin to rotate the armature and will attain sufficient momentum so that when it is brought into engagement with the contact pieces 28 it will continue to move for a sufficient distance to provide a wiping engagement with the contact members, thus keeping the contact surfaces bright. It will be noted, however, that 100 this wiping engagement occurs at the time that the current is shut off, but when current is flowing there is no movement between the contacting parts. The amount of relative movement is reduced to the minimum neces- 105

sary to keep the parts bright and never takes place when current is flowing so that the wear between the contacting parts of the make and break switch is reduced to a minimum, thus greatly increasing the life of the switch.

I claim:

1. A starting switch for a motor having a rotor, said switch comprising a contact member supported independently of the rotor and rotatable about the axis thereof, spaced stationary terminals, and means on said rotor for actuating said contact member to connect said terminals and close said switch.

2. A starting switch for a motor having a rotor, said switch comprising a contact ring, and an insulated member on said rotor arranged to engage said contact ring to close said switch and to impart temporary rotary movement by frictional force to said ring at the time the switch is closed.

3. A starting switch for an electric motor having a stationary frame and a rotor therein, said switch comprising a pair of contact members stationarily mounted on said frame, a contact ring rotatably mounted on said frame, and an insulated member mounted on said rotor for engaging said ring to close said switch.

4. A starting switch for an electric motor having a stationary frame and a rotor therein, said switch comprising a pair of contact members mounted on said frame, a contact ring mounted on said frame to rotate about an axis concentric with the axis of said motor and to move parallel with said axis, and a centrifugal governor member on said rotor for engaging said ring to close said switch when said rotor reaches a predetermined speed.

5. A starting switch for an electric motor having a stationary frame and a rotor therein, said switch comprising a stationary contact member mounted on said frame, a conductor movably supported adjacent said contact member, and an insulated member mounted on said rotor for engaging said conductor to close said switch when said rotor attains a predetermined speed, said conductor being movable by contact with said insulated member in the direction of rotation of said rotor.

6. In a starting switch for an electric motor having a stationary frame and a

rotor therein, the combination with a terminal member mounted on said frame, of a contact member for engaging said terminal to close said switch, said contact member being rotatable about the axis of said rotor, resilient means for moving said contact member out of engagement with said terminal member, and centrifugally actuated means on said rotor for moving said contact member into engagement with said terminal member, said means being adapted to impart a wiping movement to said contact member when it engages said terminal member.

7. In a starting switch for an electric motor having a stationary frame and a rotor thereon, the combination with a terminal member for the starting circuit of said motor, of a contact member rotatable about the axis of said rotor for engaging said terminal member to close said switch, centrifugally actuated means for holding said switch closed but permitting rotation of said rotor while said contact member remains stationary, said actuating means being arranged to impart movement to said contact member while closing said switch to give a wiping engagement between said contact member and terminal member.

8. In a starting switch for an electric motor having a rotor and a stationary frame, the combination with a pair of terminal members mounted on said frame at points substantially diametrically opposite one another, a contact ring for engaging said terminal members being mounted on said frame for rotation about the axis of said rotor and movable in the direction of said axis into and out of engagement with said terminal members, springs for holding said ring away from said terminal members, a ring of insulating material carried by said rotor and movable into and out of sliding contact with said contact ring, centrifugal means for actuating said insulator ring to force said contact ring into engagement with said terminal members and to impart slight rotation to said ring relative to said terminal members at the time the switch is closed by said ring.

In testimony whereof I have signed my name to this specification on this 15th day of March, A. D. 1923.

L. M. PERSONS.
